VIDEO TAPE RECORDER REEL

Hiroo Hosono and Juichi Fukushima, Osaka, and Yoshiji
Kon'i, Nara, Japan, assignors to Matsushita Electric
Industrial Co., Ltd., Osaka, Japan

Filed Nov. 14, 1972, Ser. No. 306,482

Term of patent 14 years

Int. Cl. D14—01

U.S. Cl. D26—14 B

FIG. 1

FIG. 2

FIG. 3

FIG. 4

FIG. 5

FIG. 6

FIG. 7

FIG. 8

FIG. 1 is a top, oblique perspective view of a video tape recorder reel showing our new design;

FIG. 2 is a top plan view thereof;

FIG. 3 is a bottom plan view thereof;

FIG. 4 is a sectional view taken about line IV-IV of FIG. 2;

FIG. 5 is a top, oblique perspective view of another form of a video tape recorder reel showing our new design;

FIG. 6 is a top plan view thereof;

FIG. 7 is a bottom plan view thereof; and

FIG. 8 is a sectional view thereof taken about line VIII-VIII of FIG. 6.

We claim:

The ornamental design for a video tape recorder reel, as shown and described.
